OPEN-END, SLIDABLE JAW FACE WRENCH

Earl Van Buxton, Jr., Rte. 3, Box 249, Opelika, Ala.

Filed Dec. 3, 1958, Ser. No. 777,968

1 Claim. (Cl. 81—179)

The present invention relates to a new and improved wrench for turning nuts, bolts and the like, at a minimum expenditure of time, effort and cost.

An important object is to provide the wrench with ratchet means operable upon rotation of the wrench in one direction to grip a nut or bolt, and to release the nut when the wrench is rotated in an opposite direction, so that the wrench may be turned continuously without removal from the bolt or nut to which it is applied by a backward and forward movement of the wrench handle.

A further object consists in providing the wrench with a mouth having a fixed jaw and a confronting slidable jaw face, together with a rear end wall. The confronting gripping surfaces and the rear wall are provided with co-acting transverse notches or grooves constructed and arranged to receive the corners and sides of a polygonal-shape nut or a square nut by providing a maximum of twelve gripping surfaces. By reason of this novel arrangement, means are provided for insuring the efficient operation of the wrench which permit its use in a narrow or restricted space where normally it is difficult to operate a wrench. Additionally, the structure provides means for operatively connecting the wrench to the nut to rotate the latter when it is positioned outwardly towards the forward part of the mouth as well as when the nut is positioned all the way into the wrench and in engagement with the rear wall of the mouth.

A further object consists in slidably connecting the movable jaw face to a dovetail rib that confronts the fixed jaw. The slidable jaw face is normally maintained in its inward position adjacent the rear wall of the mouth by a compression spring which is housed in the head of the wrench adjacent the handle thereof, so as to allow the wrench to be of relatively small size and in which the housing for the compression spring is recessed or drilled in such a manner that it does not weaken one side of the wrench and positions the spring in the thick and strong part of the head, with the result that the wrench is not appreciably weakened due to the formation of the spring housing.

Other objects and advantages of the invention will become apparent from the following description when taken in conjunction with the accompanying claim and drawings.

Referring to the drawings, in which is disclosed a preferred embodiment of the invention:

Fig. 1 is a perspective view of an open-end slidable jaw face wrench, constructed in accordance with the present invention;

Fig. 2 is a side elevation, with parts in section, of the head portion of the open-end wrench;

Fig. 3 is a side view of the head portion of the wrench;

Fig. 4 is an end elevational view taken substantially along line 4—4 of Fig. 1; and

Fig. 5 is an exploded perspective view of the spring assembly.

2

Referring more particularly to the drawings, 10 indicates the handle of an open-end wrench which has at one end an enlarged curved head 11 provided with a centrally disposed mouth or nut-receiving recess 12. The mouth 12 on one side thereof has a fixed jaw 13 provided with a transverse notch or groove 14 intermediate the length thereof. The opposite wall 15 of the mouth 12 is inclined downwardly and outwardly and is formed centrally with an upwardly projecting dovetail rib 16 (Fig. 4). A slidable or movable jaw face 17 shown of substantially wedge-shape, has the bottom 18 provided centrally with a channel or groove 19 of substantially the same configuration as the rib 16 so as to be longitudinally slidable on the latter when the parts are assembled. On opposite sides of the rib 16 are longitudinally extending flat top surfaces 29 (Fig. 4). The slidable jaw face 17 has an inner gripping surface 20 provided with a transverse notch or groove 21 positioned intermediate the length of the jaw face 17. The rear wall 22 of the mouth 12 is formed with a straight side 23 disposed substantially at right angles to the gripping face 24 of the fixed jaw 13 and which terminates in a substantially V-shape enlarged notch 25 having a short, inclined side 26 and a longer, inclined side 27 that intersect on opposite sides of the head 11 with the wedge or V-shape slots 28 that constitute continuations of the flat top surfaces 29 and which extend inwardly beyond the rear end wall 22. The reduced tapered inner end portions 17' of the movable jaw face 17, when the latter is in its innermost position 30 within the mouth 12, frictionally engages with a wedging action the adjacent sides of the V-shape slots or grooves 28 disposed on opposite sides of the handle 10.

The inclined side 27 of the groove 25 in the rear wall 22 of the head may be suitably drilled to form an elongated housing or recess 30 for a tension coil spring 31 to which is connected at one end an internally threaded sleeve or ferrule 32a, that in turn adjustably receives an externally threaded bolt 32. The housing 30 has a transverse web 30' through which extends the bolt 32 so as to provide an adjustable connection of the bolt with the sleeve 32a in order to control or regulate the tension of the coil spring 31. The spring 31 has an outer coil portion 33 which may terminate in an elongated straight end portion 34 of such length as to extend forwardly through a central longitudinally extending groove 35 in the top of the rib 16 (Fig. 4) and terminates in an inwardly projecting hooked end 36 that is embedded or fixed in a recess 37 (Fig. 2) in the front end of the movable jaw face 17 when the parts are assembled. The mouth 12 of the wrench is of any suitable size so as to receive a polygonal-shape nut, bolt or the like, such as the hexagonal nut 38 which has the straight sides 39 connected by the corners 40 and of such size as slidably to fit within the mouth 12 in the head 11 of the wrench.

In operation, the nut 38 to be turned is normally positioned within the mouth 12 so that a corner 40 thereof fits within the V-shape groove 25 in the rear wall 22 so that the nut is moved all the way into the mouth and assumes the position as shown in Fig. 2. It will be noted that in this position the flat sides 39 of the nut overlap the transverse grooves 14 and 21 of the jaws, and a corner 40 and its adjacent sides fit within the groove 25.

Assuming the nut 38 has right-handed threads, it will be seen that upon the rotation of the same by the wrench 65 in the direction of the arrow 41 (Fig. 2), or in a clockwise direction, the nut will be tightened to its connected member and the slidable jaw face 17 will be maintained in a fixed inward position due to the frictional engagement of the spaced tapered inner end portions 17' which now engage the sides of the V-shape slots or grooves 28. Conversely, when the pressure is released from the handle 10 and the wrench turned counterclockwise in the direction

of the arrow 42 (Fig. 3), the movable jaw face 17 is moved outwardly due to its engagement with a flat surface of the nut, causing the spring 31 to be expanded and the diametrically opposite corners 40 of the nut to temporarily fit within the adjacent notches 14 and 21. This outward movement of the jaw 17 also enlarges the width of the mouth 12, thus allowing the jaws 13 and 17 to slip over and outwardly of the notches 14 and 21, so that the movable jaw face under the tension of the spring 31 may be returned to its normal innermost position within the mouth 12 (Fig. 2) to continue either the threading of the nut to a connecting member or the removal of the same therefrom.

Thus, it will be seen that by moving or swinging the handle 10 of the wrench back and forth, a continuous rotation is imparted to the nut which allows the wrench to be turned continuously without removal of the nut or bolt from the wrench. Moreover, the spring 31 serves to maintain the movable jaw face 17 in its innermost position, as shown in Fig. 2, with the result that when the handle 10 is turned away from the jaw face 17, the latter slides out of the mouth 12 a limited distance, allowing the wrench to turn, and when this pressure is released, the spring 27 which has been expanded, functions to return the movable jaw face to its normal innermost position.

The flat top surfaces 29 of the inclined side 15 on opposite sides of the rib 16 extend inwardly beyond the inner end of the rib so as to removably fit into the slots 28. The inclined gripping surface 20 and its tapered spaced end projections 17 are disposed substantially at an angle of 15° relative to the top surfaces 29 on opposite sides of the grooves 16, so as to insure efficient operation of the wrench when securing a bolt 38 to a connecting member or removing the same therefrom. This angular inclination of the gripping face 20 with the surfaces 29, tends to insure not only a binding engagement of the nut 38 with the jaws but also freedom of engagement of the sides of the nut with the jaws so as to facilitate the efficient operation of the wrench. The polygonal nut or bolt 38 has a clearance with the adjacent walls of the mouth 12 of $\frac{1}{32}$ " to $\frac{1}{64}$ " so as to provide a sufficient angle to make the movable jaw 17 slip easier and lock tighter when the wrench is in operation.

It will be observed that the transverse notches 14, 21, and 25 coat with the side walls of the mouth 12 to provide a multi-sided gripping surface so that the wrench can be operated in a very restricted or narrow space without in any way impairing its efficiency. Moreover, the dovetail connection of the movable jaw face with the head and the housing of the spring 31 provides means for constructing or making a relatively small size wrench and one that may be efficiently used in small or restricted areas. In this connection, it might be noted that wrenches of this general type, as previously made, are rather bulky or heavy and only capable of use with very large nuts in readily accessible places. Heretofore, associating slidable jaws faces with wrenches required T-slots and the use of a large wrench in order to preserve enough strength to make it useful. In the present invention, on the other

hand, the recessing and drilling of the housing 30, in which is positioned the tension spring 31, is done in such manner that the housing is formed in a strong part of the wrench so that the jaws are not materially weakened as is quite frequently the case in wrenches of this type as heretofore constructed. It will be noted that the wrench will efficiently work with the nut 38 in the outer end of the jaws, as contrasted to the prior teaching in the art in which the nut has to be moved fully into the jaw before the wrench will operate.

Thus, it will be seen that the wrench may be either of large or small size and dispenses with the use of relatively heavy wrenches which require boring out of the recess or the use of a pin to extend through the spring, thus necessitating relatively heavy pieces of metal to make the wrench. It will be manifest that the wrench may be provided at each end with an enlarged head, shaped to receive means for operating a nut or bolt.

It will be understood that the form of the invention shown is merely illustrative and that such changes may be made as come within the scope of the following claim.

I claim:

A wrench for polygonal-shape nuts, bolts and the like, including a handle having a head at one end, said head having a nut-receiving mouth forming a fixed jaw, a confronting inclined side and rear wall, said fixed jaw having a transverse notch intermediate the length thereof, said inclined side having a dovetail rib extending upwardly and longitudinally thereof, a movable jaw face having a bottom provided with a longitudinally extending groove slidably connected to said rib, said movable jaw face having an inclined inner gripping surface confronting said fixed jaw and a transverse notch in said surface, said rear wall having a straight side intersecting the inner end of said fixed jaw and a substantially V-shape notch connected at one end to said straight side, said V-shape notch having one side thereof longer than the other side, the longer side of said notch having an elongated recess extending into said head so as to form a housing, a coil tension spring in said housing, said spring having an inner end and an outer end, an internally threaded ferrule connected to the inner end of said spring, said housing having a transverse web provided with an opening, an externally threaded bolt extending through said opening into engagement with the threads of said ferrule so as to control the tension of said spring, and the outer end of said spring being connected to said slidable jaw face for normally urging the same inwardly towards said rear wall.
